FIRE SCREEN UNIT FOR VOLATILE LIQUID STORAGE RECEPTACLES

Filed Dec. 1, 1930

UNITED STATES PATENT OFFICE

1,983,417

FIRE SCREEN UNIT FOR VOLATILE LIQUID
STORAGE RECEPTACLES

John J. Tokheim, Cedar Rapids, Iowa

Application December 1, 1930, Serial No. 499,399

2 Claims. (CL. 220—88)

This invention relates to the art of storing volatile, inflammable liquids, and has in view to provide improved means for connection with storage receptacles for such liquids to protect the contents of the receptacles against fire.

As is well known, it is necessary to vent volatile liquid receptacles of any appreciable capacity, such as gasoline storage tanks and the like, in order to permit the relief of pressures and partial vacuums which may tend to develop in such receptacles. It follows, therefore, that in the event of a fire in the vicinity of a vented volatile liquid storage receptacle, and in the absence of means to prevent flame from reaching the contents of the receptacle through the vent opening thereof, the contents of the receptacle are extremely likely to become ignited. Accordingly, the general object of the present invention is to provide a device which is constructed to permit free venting of a storage receptacle with which the same may be used; and which is effective to prevent any flame from reaching the contents of the receptacle through the vent opening thereof.

Another object of the invention is to provide a device of the character mentioned which is of simple, inexpensive construction, which is strong and durable and fully capable of withstanding any explosive forces to which the same may be subjected in use, which is adapted for outside use, where it may be exposed to the elements, and which is thoroughly reliable and efficient in use.

With the foregoing and other objects in view, the invention consists in the novel features of construction, combination and arrangement of parts as will be hereinafter more fully described, illustrated in the accompanying drawing and defined in the appended claims.

In the drawing, wherein like characters of reference denote corresponding parts in the different views:—

Figure 1 is a vertical section through a relief valve for volatile liquid storage tanks showing the present fire screen device operatively connected therewith.

Figure 2 is an end view of the present device.

Figure 3 is an enlarged detail section through a portion of the present device; and

Figure 4 is an enlarged elevation of one of the numerous duplicate plate elements included in the present device.

While the present fire screen device may be used in conjunction with volatile liquid storage receptacle relief valves of various different types, and may, in fact, be directly connected with a storage receptacle in covering relation to the vent

opening therein, the same, according to the embodiment thereof illustrated in the drawing, is especially adapted for use in conjunction with relief valves of the type illustrated in my copending application Serial Number 353,833. Accordingly, said device has been illustrated in the present instance as being disposed in covering relation to the vapor outlet and air inlet opening of a relief valve of the type disclosed in my said copending application. It will be understood, however, that this has been done merely to bring out the utility of the device, and that such illustration therefore is not to be construed as in any way limiting the range of use of the device.

A relief valve of the type disclosed in my copending application and as illustrated in Fig. 1 of the present drawing, comprises a casing A inclusive of a pair of cylinders or chambers 10 and 11 disposed in side to side relation with their interiors connected with one another by a lateral passage 12, the chamber 10 being adapted for connection with a volatile liquid storage tank 1 (not shown) by means of a pipe 13, for example, and the chamber 11 having a pair of valves 14 and 15 disposed therein to respectively control the escape of vapor from the tank and the inlet of air to the tank through a vent opening in the lower end of the valve chamber 11.

The present fire screen device is composed of a plurality of duplicate ring-like plates 16 formed preferably from suitable rustproof metal such as aluminum, and in accordance with the invention each of these plates is provided, preferably near its periphery, with a plurality of circumferentially spaced rivet receiving apertures 17 and, between each adjacent pair of said apertures, with other fastener receiving apertures 18.

In forming the plates 16 the rivet receiving apertures 17 preferably are punched therein, and during this operation a suitable die or dies preferably is or are employed to deflect the metal of the plate directly surrounding each of said openings laterally beyond the plane of one side of the plate, thereby to provide, in surrounding relation to each of said apertures, a spacing bead 100 or protuberance 19. However, the apertures 17 and the beads 19 may be formed in any other manner and any other suitable spacing means may be provided in lieu of the beads 19.

Also in forming the plates 16 the metal of each plate preferably is deflected laterally at suitably spaced points in the same direction as the beads 19 to provide other spacing protuberances 20, which protuberances are arranged preferably in two concentric series, those of one series

being disposed in pairs one to either side of each aperture 18, and those of the other series being disposed adjacent to the central opening 21 in the plate, the result being that the several 5 protuberances of each plate are disposed in staggered relation.

To construct a fire screen unit from the plates 16, a desired number of said plates are superimposed upon one another with the apertures 10 17 and 18 of the several plates disposed in alignment with one another and with the protuberances of the respective plates all facing in the same direction, whereby the plates are held by said protuberances in slight spaced relation, thus 15 to provide a narrow slit 22 between each adjacent pair of said plates. In addition, a flat closure plate 23 is disposed against one of the end plates of the unit, and the several plates 16 and the closure plate 23 then are secured together in a 20 unitary assembly by means of preferably hollow rivets 24 passed through the apertures 17 of the several plates 16 and through aligned apertures in the plate 23.

The rivets 24 serve to hold the plates of the 25 unit with the fastener receiving apertures 18 of the plates 16 in alignment with one another and in alignment with corresponding apertures formed in the closure plate 23, and thus, to 30 secure the unit in covering relation to the vent opening in the lower end of the chamber 11 of the valve casing A, all that is necessary is to pass bolts 25 through the fastener receiving openings of the unit and thread said bolts into threaded apertures previously provided in the casing A.

In the unitary assembly of the plates 16 and 35 23, it is apparent that the central openings 21 of the plates 16 align with one another to provide a central passage through the unit, which 40 passage opens through the inner end of the unit and is closed at the outer end of the unit by the plate 23. With the unit secured in covering 45 relation to the vent opening in the valve casing A it thus follows that air is permitted to pass freely through the slits 22 between the various 50 plates of the unit into the central passage in the unit and through the valve A to the liquid storage tank to relieve any partial vacuum which 55 may tend to form in the tank, and that likewise, in the event of pressure developing in the storage tank, the escape of vapor from the tank through the valve A and the slits 22 of the fire screen unit is permitted to relieve such pressure. On the other hand, due to the relatively narrow width of the slits 22, flame is effectively prevented from reaching the interior of the unit and any danger of the contents of the tank becoming ignited by reason of a flame in proximity to the vent opening of the valve A is eliminated.

60

Preferably, a wire screen 26 of suitably fine mesh is interposed between the inner end of the fire screen unit and the valve A to exclude dust and other foreign matter from the valve chamber. Preferably, too, the lower end of the valve 80 casing A is formed with a depending annular lip 27 disposed outwardly of the fire screen unit for the purpose of causing rain water and the like to drip from the valve casing without contact with the fire screen unit. The use of a screen 26 and the provision of the lip 27 are optional considerations, however, as will be understood.

In view of the foregoing it will be apparent, as heretofore stated, that the present unit may be used either with other types of relief valves 90 or in direct covering relation to the vent opening of a tank. It will likewise be apparent that the size and shape of the unit may be varied to suit particular conditions of use thereof, and that various modifications of the specific structural 95 arrangement illustrated may be resorted to within the spirit and scope of the invention as defined in the appended claims.

I claim:—

1. A flame screen unit comprising a series of 100 ring-like plates disposed in superimposed relation, each plate having a plurality of openings to receive fasteners for securing the plates together and further having other openings to receive fasteners for securing the unit in covering relation to a tank vent opening, protuberances integral with said plates surrounding each of said first mentioned openings of each plate to hold the plates in slight spaced relation in the vicinity of said openings, other protuberances carried by 110 each plate serving to hold other portions of the plates in spaced relation, all of said protuberances contacting directly with the next adjacent plate, a closure member for one end of the unit, and fasteners extending through said closure 115 member and through said first mentioned openings to secure the plates and said closure member in assembly with one another.

2. The combination with a tubular member having one side communicating with a storage 120 vessel for volatile liquids and having its other side communicating with the atmosphere, of a flame arrester device arranged at the atmosphere side of said tubular member and capable of preventing propagation of flame from the exterior to the interior thereof, said device comprising a stack of spaced-apart plates having their outer edges exposed directly to the atmosphere, and each of said plates having a central opening providing a passageway communicating with 130 said tubular member, and an exposed cover member fitted to the outermost plate of the stack to close said passageway.

JOHN J. TOKHEIM.
